Edward H. Shelley

BY

Mr. Wallace White

ATTORNEY

UNITED STATES PATENT OFFICE.

EDWARD H. SHELLEY, OF RIDGEWOOD, NEW JERSEY.

BARREL-BUNG.

1,331,083.

Specification of Letters Patent. Patented Feb. 17, 1920.

Application filed February 28, 1919. Serial No. 279,785.

To all whom it may concern:

Be it known that I, EDWARD H. SHELLEY, a citizen of the United States, residing at Ridgewood, Bergen Co., New Jersey, have 5 invented new and useful Improvements in Barrel-Bungs, of which the following is a specification.

My invention relates to a bung for closing and sealing the bung holes of receptacles such as barrels, casks, and the like, and 10 it has for an object the provision of a metallic bung for wooden barrels which utilizes the walls of the bung hole to permanently secure the bung therein, thus eliminating 15 the use of bushings or other additional means, and thereby producing a bung which is cheap, and easily and quickly applied to the bung hole.

A more specific object of the invention is 20 the provision of a bung formed of a ductile metal wherein the bottom of the bung is of concavo-convex formation to permit the adjacent portions of the side walls to be flexed outwardly to engage the inner edge 25 of the bung hole, while at the same time the concavity of the bottom not only reinforces the bung, but utilizes the pressure of the contents of the barrel to force the bung into more intimate contact with the inner 30 edge of the bung hole.

I will describe one form of my invention, and will then point out the novel features thereof in claims.

In the accompanying drawings, Figure 1 35 is a view showing in side elevation and partly in section one form of bung embodying my invention and before the same is applied to the bung hole.

Fig. 2 is a similar view showing the same 40 applied and locked within the bung hole of a barrel.

Referring specifically to the drawings, and particularly to Fig. 1, B designates a 45 ductile metal bung of substantially cup-shaped formation, the side walls 10 thereof converging toward the bottom wall 11 to snugly fit the inclined walls of the usual tapered bung hole H shown in Fig. 2. The upper or outer end of the bung B is formed 50 with an annular flange 12 which is arranged at approximately right angles to the side walls 10 and has its marginal edge inturned as at 13. The bottom wall 11 is concaved to an appreciable degree so as to allow the 55 bending of the side walls 10, at the same

time maintaining, in a lesser degree, its concavity when in the final locked position, as shown in Fig. 2.

When the bung B is applied within the bung hole H, as shown in Fig. 2, the flange 60 12 rests upon the outer marginal edge of the bung hole and thus limits the inward movement of the bung within the hole. The bung B is designed so that when in position within a bung hole, its inner end projects 65 a slight distance beyond the inner wall of the barrel.

With the bung in applied position, a suitable expansible tool is inserted within the bung and rotated to form simultaneously a 70 plurality of separate and independent annular grooves 14, which in turn form annular beads 15 which embed themselves within the walls of the bung hole. This operation secures the bung in a permanent, 75 rigid, and fixed position, it being understood that the annular beads 15 coact with corresponding beads 16 formed on the walls of the bung hole as a result of embedding the beads 15 in the walls of the bung hole. 80 By providing a plurality of annular grooves 14, I eliminate the possibility of the contents of the barrel seeping through the bung hole, as each groove being independent of adjacent grooves, the channels formed by 85 the beads 15 do not communicate with each other and therefore do not provide a continuous channel, as is the case when forming a spiral groove.

In the present instance, I have shown the 90 bung formed with four grooves 14, the lowermost groove of which is contiguous to the bottom wall 11 and, as shown the corresponding bead 15 abuts the inner wall of the barrel, thereby forming an additional locking means for preventing displacement of the bung. When forming this lowermost bead 15, the metal of which the bung is formed stretches to a certain extent owing to the ductile quality of the metal, and in 100 so doing forces the bottom wall 11 outwardly to a small degree, thus reducing its concavity. However, it does not completely destroy its concavity but assumes the shape shown in Fig. 2, so that the pressure exerted 105 by the contents of the barrel is distributed uniformly to the periphery of the wall thereof and directly upon the lowermost bead 15. This in turn forces the bead into snug engagement with the inner edge of the 110

bung hole, and thus forms an additional means for positively maintaining the bung in fixed position.

When the contents of the barrel are required for use, the bottom wall of the bung is usually pierced, thus destroying the seal and indicating that the contents have been tampered with.

From the foregoing description taken in conjunction with the accompanying drawings, it will be manifest that I have provided a simple and efficient form of bung which may be easily and quickly secured within the bung hole, and which eliminates the use of additional means for confining the bung within the bung hole.

Although I have herein shown and described only one form of bung embodying my invention, it is to be understood that various changes and modifications may be made herein without departing from the spirit of the invention, and the spirit and scope of the appended claims.

What I claim is:

- 25 1. A bung comprising a single sheet of ductile metal of cup-shaped formation having a concavo-convex bottom, and a rib formed in the side walls of the bung in close proximity to the bottom, the bottom being adapted when pressure is exerted on the convex side thereof, to expand said rib.
2. In combination, a receptacle having a bung hole formed therein, an integral cup-shaped bung of ductile material fitting

within said hole and having its closed end 35 projecting beyond the inner wall of the receptacle, and a continuous rib formed on the projecting portion of the bung after the bung is placed in position within the bung hole.

3. A combination as embodied in claim 2, wherein the bottom wall of the bung is of concavo-convex formation.

4. In combination, a receptacle having a bung hole formed therein, a ductile metal 45 bung snugly fitted within said hole, an annular flange formed on the open end of the bung and arranged to limit the inward movement of the bung within the hole, the inner end of the bung projecting beyond the 50 inner wall of the receptacle and having its bottom concaved, and a plurality of circumferentially extending ribs formed exteriorly of the bung by outstriking the same after the bung is placed in the bung hole, 55 one of said ribs being formed on the projecting end of the bung and engageable with the inner edge of the walls of the bung hole.

5. A bung, comprising a cup-shaped member formed of a single sheet of ductile material having the bottom wall thereof of concavo-convex formation, and a plurality of complete ribs formed thereon each separate from adjacent ribs and the innermost rib merging into said bottom.

In testimony whereof I have signed my name to this specification.

EDWARD H. SHELLEY.
